UNITED STATES PATENT OFFICE

2,650,512

PIPE WRENCH WITH NUT FULCRUMED
PIVOTED OUTER JAW

Walter J. Johnson, Buffalo, and Carl G. Ertell, Eggertsville, N. Y., assignors to J. H. Williams & Co., Buffalo, N. Y., a corporation of New York

Original application July 14, 1950, Serial No. 173,904. Divided and this application November 21, 1951, Serial No. 257,464

6 Claims. (Cl. 81—101)

1

The invention disclosed herein is a division of the invention disclosed in our co-pending application, Serial No. 173,904, filed July 14, 1950.

The invention relates to pipe wrenches of the type having a floating or movable hook jaw and aims to provide certain improvements therein.

In the prior art devices of the class to which the present invention is directed, certain inherent shortcomings have been recognized, for example, the springs which floatingly support the hook jaw broke because of faulty design, or when the wrench was used as a hammer; it was often difficult to replace broken springs; and the prior construction frequently failed to provide a full floating action for the hook jaw.

Accordingly, the present invention has for its object the elimination of the defects in prior wrench constructions, as above pointed out.

A further object of the invention is to provide a novel spring suspension for the floating jaw.

A still further object is to provide a wrench of the type set forth wherein the springs will be under compression in all positions of the floating jaw.

A still further object is to provide a spring in the mounting which forms a compressible and dynamic pivot point for the jaw shank, thus elastically suspending the jaw through its full angular movement, except at the two extremes of such movement.

The accomplishment of the foregoing and other objects of our invention not specifically enumerated will become apparent to persons skilled in the art from the detailed description which follows, when considered in connection with the accompanying drawings, wherein:

Figure 1 shows a side elevational view of a wrench, with part of the handle broken away and shown in section, and with parts of the frame broken away and shown in section to better illustrate the novel features of the invention.

Fig. 2 shows a sectional view taken along the plane of the line 2—2 of Fig. 1.

Figs. 3 and 4 show side elevations of the springs employed in providing the floating jaw suspension of the wrench.

Referring to the drawings, in the various figures of which corresponding parts are designated by the same reference characters, the pipe wrench comprises a handle 10 having a fixed jaw 11 and an integral frame or housing 12 through which extends a threaded shank 13 of a movable jaw 14, which is adjustable relatively to the jaw 11 by a nut 15 engaging the threads on the shank, said nut being disposed and retained between the

bottom of the frame 12 and a pair of bosses 16 formed integrally with the handle, the bottom of the frame 12 serving as a fulcrum for the nut 15 during use of the wrench. The jaws 11 and 14 may be provided with replaceable jaw inserts 17 and 18, respectively, herein shown as connected to the jaws by dovetail joints. The recited elements in their cooperative relationship set forth are conventional in pipe wrenches and no claim is here made to said general combination.

According to the present invention the movable jaw 14 is resiliently suspended in the frame 12 by two springs 21 and 20 which are removably mounted in the frame at the front and rear thereof, respectively. The spring 20 is formed of a strip of flat, resilient metal which is bowed from end to end and has its ends 22 bent rearwardly. The spring is mounted in the frame with the ends 22 seated in recesses 24 in the rear of the frame, and with the body of the spring disposed in a channel 24 formed in the rear wall of the frame between the recesses 23 to allow for flexing of the spring. The spring 21, which is also formed of a flat strip of resilient metal, is of flattened Z shape and is mounted within a channel 25 in the front wall of the frame by having one end of the spring, which is formed with a forwardly bent portion 26, seating in a recess or hole 27 extending from the channel 25 into the rear of the fixed jaw 11. The intermediate arm 28 of the Z spring 21 has its end portions 29 deflected to lie in substantially parallel planes and to also lie in abutting relation to the adjacent end portions of arms 30 and 31 to permit of ready flexing of the spring without breaking. The springs 20 and 21 are mounted within the frame so as to be under compression in all jaw shank positions and the bowed spring 20 forms a compressible and dynamic rocking or pivot point for the movable jaw shank, which is thereby resiliently suspended through its full angular movement in the course of the use of the wrench, except at its two extreme positions of angular movement where the jaw shank acting through the spring bears against either the top or bottom of the rear wall of the frame. The Z spring 21, because of its shape and disposition in the frame at all times has at least one of its arms subjected to tensioned stress.

Pipe wrenches made in accordance with the foregoing disclosure fully satisfy the various objects of the invention recited in the opening statement of this specification, and while we have shown and described a preferred embodiment of our invention it is to be understood that

changes in the details of construction set forth may be made within the range of mechanical and engineering skill without departing from the spirit of the invention as hereinafter claimed.

What we claim is:

1. In a pipe wrench comprising a handle provided with a fixed jaw and a frame, a movable jaw having a shank extending through said frame and spring means within the frame resiliently suspending the shank of the movable jaw, characterized in that the spring means consist of two separate springs removably mounted in the frame, one at the front and the other at the rear of the frame, one of said springs being bowed inwardly of the frame and at its mid-point 15 being substantially tangent to the shank of the movable jaw and providing a rocking or pivot point for the movable jaw shank.

2. A pipe wrench according to claim 1 where-
in the front spring is of flattened Z form and has 20
the end portions of the oblique arm connecting
the top and bottom arms of the Z extending in
substantially parallel abutting relation to the said
top and bottom arms.

5
10

3. A pipe wrench according to claim 1 where-
in the bowed spring extends from end to end longitudinally of the frame and has its ends bent rearwardly and seated in recesses in the frame.

4. A pipe wrench according to claim 1 where-
in the rear spring is bowed inwardly of the frame to provide the rocking or pivot point for the movable jaw shank.

5. A pipe wrench according to claim 4 where-
in the spring is bowed from end to end longitudinally of the frame and has its ends frictionally anchored on the frame.

6. A pipe wrench according to claim 4 where-
in the front spring is of flattened Z form.
